UNITED STATES PATENT OFFICE.

CLAUDE A. P. TURNER, OF MINNEAPOLIS, MINNESOTA.

FIREPROOF FLOORING.

1,320,186.

Specification of Letters Patent.

Patented Oct. 28, 1919.

Application filed June 21, 1916. Serial No. 104,877.

To all whom it may concern:

Be it known that I, CLAUDE A. P. TURNER, a citizen of the United States, residing at Minneapolis, in the county of Hennepin and 5 State of Minnesota, have invented certain new and useful Improvements in Fireproof Flooring, of which the following is a specification.

My invention relates to fire-proof flooring 10 and has for its object to provide a combination tile and concrete floor supported by walls or beams such as reinforced concrete beams or other form of beams, the tile being so fabricated as to form a true voussoir flat 15 tile arch, the portions of the tile abutting and providing open recesses in which the concrete flows as poured to form a key or keys for the arch. I further provide on portions of the tile which come at the haunch 20 of the arch projections so that when the concrete has been poured and set the voussoir arch as a whole is locked or anchored in the concrete against downward as well as other displacement.

25 The full objects and advantages of my invention will appear in connection with the detailed description thereof and are particularly pointed out in the claims.

In the drawings, illustrating the application 30 of my invention in one form,—

Figure 1 is a sectional view of a portion of a floor embodying my improvements. Fig. 2 is a sectional view of a portion of the floor showing voussoir arches formed of 35 pairs of tile. Fig. 3 is a similar view showing an arch formed of three tiles.

In the practice of the invention satisfactory results are obtained by fabricating the tile on a twelve inch press and cutting the 40 same in twelve inch lengths. It thus follows that the two-tile arch of Fig. 2 will be approximately two feet in breadth while the three-tile arch of Fig. 3 will be three feet in breadth.

45 Referring to Fig. 2, tile members 10 and 11 are respectively formed with curved portions 13 and 14, the tile members, of course, being identical as fabricated but being positioned symmetrically in the arch. The upper 50 portion of each tile member is cut away from a vertical line so that when the tile are positioned with the lower portions abutting each other a space indicated at 15 is left into which the concrete can flow to form a key. The tile members are formed with projections 16, 17 at the lower

portion of curves 13, 14, which results in locking the arch into the floor when the concrete has set. Reinforcement 18 may be employed between the arches 19 formed by 60 the tile.

As shown in Fig. 3, blocks 20 and 21, similar in character, are symmetrically positioned in an arch 22 so that their curved portions 23 and 24 extend in opposite directions, terminating in projections 25 and 26, similar to the projections 16 and 17 of blocks 10 and 11. In this form a center block 27 is employed formed with ledges 28, 29 adapted to rest upon corresponding ledges 30, 31 of blocks 20 and 21 when the lower portions of said blocks are respectively in abutting position. The adjacent sides of the upper portions of blocks 20, 27 and 21, 22 are so formed as to leave spaces 32 and 33 70 into which the concrete may flow to form keys similar to the keys 15 previously described.

In practice the floor may be fabricated either in conjunction with or after the erection of the beam construction for supporting the same. A staging is set up between the beams or in conjunction with beam forms and the blocks set in position upon the staging to form the voussoir arch structure 19 80 or 22, according to the form of tile employed. The reinforcing members 18, if used, are placed in position between the voussoir arches, and the concrete, indicated generally by 34, is poured. This flows into the key openings 15 or 32, 33 and beneath the haunch projections 16, 17 or 25, 26, forming large compression flanges 35 of concrete and keying the arch members 19 or 22 and also locking said arch members into the floor 90 by reason of said haunch projections.

The advantages of this construction will be apparent. The tile may be made relatively light, may be economically fabricated and can be positioned in the floor by comparatively unskilled labor. The resulting floor structure will be light in weight in proportion to its load-supporting capacity. The arches are true voussoir arches in which the keys are formed of concrete during the 100 pouring of the same and are effectively locked or anchored in the floor by the projections at the haunch of the arch. It will be understood that many different forms of tile may be fabricated embodying the improvements of my invention and corresponding 105 differences in the shape and dimension 110

of the arches would result; and I do not wish to be limited to the precise form or detail of the structures herein shown and described.

5 I claim:

1. A combination tile and concrete floor comprising a tile voussoir flat arch composed of blocks, the adjacent faces of which abut each other in their lower portions and diverge from each other in their upper portions to provide recesses of considerable depth extending across the faces of the blocks, and concrete above and at the sides of said arch and in said recesses.
- 10 2. A combination tile and concrete floor comprising a tile voussoir flat arch composed of blocks, the adjacent faces of which abut each other in their lower portions and diverge from each other in their upper portions to provide recesses of considerable depth extending across the faces of the blocks, and concrete above and at the sides of said arch and in said recesses, some of said blocks having projections at the haunches of the arch for anchoring the arch in the concrete.
- 15 25

3. A combination tile and concrete floor comprising a series of tile voussoir flat arches composed of blocks, the adjacent faces of which abut each other in their lower portions and diverge from each other in their upper portions to provide recesses of considerable depth extending across the faces of the blocks, and concrete above and between said arches and in said recesses.

4. A combination tile and concrete floor comprising a tile voussoir flat arch formed of two series of said blocks and a series of central blocks, the side blocks and the central blocks having their adjacent faces abutting each other in their lower portions and having their faces diverging from each other in their upper portions to provide recesses of considerable depth extending across the faces of the blocks, and concrete above and at the sides of said arch and in said recesses.

In testimony whereof I affix my signature in presence of two witnesses.

CLAUDE A. P. TURNER.

Witnesses:

F. A. WHITELEY,
F. A. CAMP.
